ATTORNEY

UNITED STATES PATENT OFFICE

CARL WIRTH, OF ROCHESTER, NEW YORK

ANTIRATTLING DEVICE

Application filed June 29, 1931. Serial No. 547,630.

This invention relates to anti-rattling devices adapted for use in combination with windows, screens or any other members which are loosely mounted and have a tendency to rattle in their mounting and the object of this device is to provide a device of this character which is easily attached and operated to take up the undesired motion of the members which cause the rattling.

Another object of this invention is to construct the parts of the device so that they may be made from sheet metal at a minimum cost and easily assembled without the use of any hand tools.

Other objects and attendant advantages will become more readily apparent from the detailed description of the device which follows, reference being had to the accompanying drawing in which

Figure 1 is a vertical sectional view of a portion of two windows with the anti-rattling device mounted on one of the windows to keep them from rattling.

Figure 2 is a perspective view of the anti-rattling device.

Figure 3 is a longitudinal sectional view of the anti-rattling device as it appears in its operative position.

Figure 4 is a similar longitudinal sectional view of the device as it appears in its inoperative position.

Figure 5 is a detail perspective view of the bolt of the anti-rattling device.

Figure 6 is a bottom plan view of the bolt of the anti-rattling device.

Figure 7 is a detail perspective view of the operating link of the anti-rattling device.

Figure 8 is a detail perspective view of the housing of the anti-rattling device.

Figure 9 is a detail perspective view of the base of the anti-rattling device.

Figure 10 is a bottom plan view of the device with the base removed from it and the parts in the position illustrated in Figure 4.

In the several figures of the drawing like reference numerals indicate like parts.

The anti-rattling device, forming the subject matter of my present invention, is, except for the contact or cushioning member and the spring member, entirely made up of

sheet metal parts blanked out and formed in a punch press practically ready to be assembled. As illustrated in the several figures the anti-rattling device comprises a housing 1 which is open at the bottom and one end, while the other end thereof is closed by the curved back 2 which has the cam slot 3 provided therein. The link 4, with which the device is operated, is adapted to travel back and forth in the slot 3 as will hereinafter be described.

Projecting from either side of the bottom of the housing 1 are the horizontal flanges 5 and 6 which have the eyelets 7 and 8 struck out therefrom for a purpose that will presently appear. The housing 1 is mounted on the base plate 9 which has the outline of the bottom of the housing and is provided with a pair of holes 10 and 11 which register with the eyelets 7 and 8 of the housing to have them project thereinto and be expanded therein so as to firmly fasten and lock the base plate to the housing and close the bottom thereof.

Mounted to slide in and out of the open end of the housing 1 is the bolt 12. This bolt has the pocket 13 formed in the front end in which the rubber contact pad 14 is held in place. For this purpose small lugs 15 are struck in on the sides of the bolt 12 to project into the side of the rubber pads and keep them from sliding out of the pocket after being placed therein. A rounded knob 16, formed by the outer end of the rubber pad, projects from the end of the pocket 13 and provides the contact surface for the end of the bolt. The bolt has a pair of vertical parallel guide flanges 17 and 18 extending rearwardly of the pocket 13 which serve to guide the bolt in a straight line movement in the housing 1. The metal portion of the bolt 12 is formed up of a single metal blank in such a manner that the ends of the blank portion, which form the bottom of the pocket 13, abut and are locked together by the engagement of the lug 19 formed on one end of the blank into the notch 20 formed in the other end of the blank as illustrated in Figures 6 and 10. The end of the pocket 13 in the bolt 12 is formed by an extension 21 of the

top of the pocket which is bent down at right angles thereto. Projecting rearwardly from the pocket 13 intermediate of the guide flanges 17 and 18 and parallel thereto is the 5 spring supporting member 22. This member is a continuation of the blank portion forming the back 21 of the pocket 13 which is reduced in width to have the expansion spring 23 telescope thereover.

10 The outer end of the spring supporting member 22 projects thru the hole 24 provided in the lug 25 and is struck up from the base plate 9 at right angles thereto. The expansion spring 23, which surrounds the 15 supporting member, is located between the lug 24 and the back of the pocket 13 and the location of the lug with relation to the back of the pocket is such that the spring is held under tension between these two parts when 20 the bolt is in its outer or operative position illustrated in Figures 1, 2 and 3.

To move or withdraw the bolt from the yielding operative position to the non-yielding inoperative position, illustrated in Figures 4 and 10, the link 4 is provided. This link is bifurcated at one end and the outer ends of the bifurcation have the laterally projecting lugs 27 and 28 provided thereon which engage into the notches 29 and 30 formed in the bottom of the guide flanges 17 and 18. The intermediate portion of the link, which is of narrow width, projects thru the cam slot 3 in the curved back of the housing 1. On the outside of the housing the link 5 is enlarged to form a handle thereon which overhangs the cam slot on each side thereof.

In the operative position the expansion of the spring 23 forces the bolt 12 and with it the link 4 to the left until a further movement 40 of the link to the left is arrested by the engagement of the overhanging portion of the handle thereof with the left hand end of the curved cam slot 3. This position is illustrated in Figures 1 to 3 and in this position the pressure of the spring 23, transmitted to the bolt 12, is applied to the member which is to be held from rattling. In the mounting of the device it is desirable that the bolt will make contact with the member which is 45 to be held from moving and rattling before it has reached its extreme outer position so that the bolt will be forced against this member by a tension of the spring which will keep the member from rattling.

50 In the case of windows, this lateral force will not prevent the windows from sliding up or down while making contact with the bolt because the rubber contact members at the end of the bolt will give due to the spring tension in back of it and also readily slide over the surface of the window frame without marring the finish of it.

To release the anti-rattling device the handle of the operating link 4 is forced to the 60 right so that the overhanging portion thereof

slides over the curved back of the housing and draws the link and with it the bolt 12 to the right against the pressure of the spring 23. At the end of the slot in the back of the housing the link is practically in line with the spring, while its overhanging handle portion is located on a practically straight surface on the outside of the back of the housing. In this position the link is automatically held against a return movement so that the bolt will remain in the inoperative position until the handle of the link is again raised to a point where the expansion of the spring can draw the link back to its starting position over the curved back of the housing.

Of course the anti-rattling device shown and described may be changed in various ways, and variations may be required under certain conditions, therefore, while some of the constructional details are deemed preferable and I have shown and described these in detail, it is to be understood that I do not limit myself to such precise construction but consider that I am at liberty to make changes and alterations as fairly come within the scope of the appended claims.

I claim:

1. An anti-rattling device comprising a housing, a fixed cam formed by the back of said housing, a spring pressed bolt mounted to slide in and out of the front of said housing and operating means adapted to slide over said cam and pivotally connected to said bolt within the housing to move said bolt in one direction.

2. An anti-rattling device comprising a housing, a curved wall closing one end of said housing and having a slot therein, a bolt mounted to slide in said housing, a link connected to said bolt and projecting thru said slot in said curved wall, and means carried by said link and adapted to slide over the outside of said wall to move said bolt in one direction in said housing.

3. An anti-rattling device comprising a housing, a bolt mounted to slide in and out of said housing, a spring supporting member carried by said bolt and projecting rearwardly thereof, a spring surrounding said supporting member, a link pivoted on said bolt, a cam formed by the back of said housing and operating means provided on said link and extending thru the back of said housing and engaging said cam to draw said bolt into said housing on the movement of said operating means over said back of said housing.

4. An anti-rattling device comprising a housing, a bolt mounted to slide in and out of said housing, a spring supporting member carried by said bolt, a spring surrounding said supporting member, a bifurcated link straddling said supporting member and said spring and engaging said bolt on each side thereof, and cam means operating to move said link

and draw said bolt in one direction against the pressure of said spring.

5. An anti-rattling device comprising a housing, a bolt mounted to slide in and out of said housing, a pair of vertical guide flanges projecting rearwardly of said bolt and having a notch in the bottom thereof, a spring supporting member carried by said bolt and projecting rearwardly thereof between said guide flanges, a cam formed at the end of said housing, a link engaging said notches in said guide flanges with one end thereof, and means provided at the other end of said link to engage said cam.

10 6. An anti-rattling device comprising a housing open at the front and bottom thereof, a bolt mounted to slide in and out of the open front of said housing, a spring supporting member carried by said bolt and projecting rearwardly thereof, a base for said housing, a lug struck up from said base into said housing, said spring supporting member being mounted to slide in said lug, a spring carried by said spring supporting member and interposed between said lug and said bolt to normally move said bolt in one direction, a vertically disposed cam formed at the rear of said housing, a link pivotally mounted to said bolt and mounted to swing in a plane at right angles to said base and means carried by said link and engaging said cam to draw said bolt in the opposite direction against the pressure of said spring on the swinging of said link to the rear of said housing.
